MEANS FOR CLOSING SEALING RINGS

Edgar E. Shanor, Sharon, Pa., assignor to The
Petroleum Iron Works Company of Ohio,
Sharon, Pa., a corporation of Ohio

Application May 6, 1937, Serial No. 141,150

5 Claims. (Cl. 220—46)

The invention relates generally to devices for securing and sealing the heads of shipping drums, barrels, pails and other containers of the type in which the cover is embodied in a head for a substantially open end container or the cover is applied to a necked opening in the head.

In Letters Patent No. 2,081,877, I have described and claimed an assembly for securing and sealing the heads of shipping drums and the like in which a so called slack take up member is mounted for angular movement between the spaced apart ends of the conventional U-ring or channel. My present invention is a continuation of that inventive thought and provides simple, efficient and inexpensive means for securing the parts after the slack take up member has been operated to contract the ring.

The nature, characteristic features and scope of the invention more readily will be understood from the following description, taken in connection with the accompanying drawing, forming a part hereof, wherein

Fig. 1 is a sectional view of a container having an opening sealed in accordance with the invention.

Fig. 2 is a plan view, and Fig. 3 is an edge view of the slack take up member and its accessories in the open position of the sealing ring.

Fig. 4 is an edge view partly in section showing the relation of the parts in the closed position.

In the drawing, the numeral 5 represents a container having an opening terminating in a circumferential bead 6 which supports a sealing gasket 7 for the overlying flange 8 of a slip cover 9; and 10 represents a split ring or chime whose channular walls, when the ring is contracted, serve to apply clamping action in the well-known way to the bottom of the bead and to the top of the cover flange.

According to the invention a closing member is provided between the spaced apart ends of the chime for drawing them towards each other in such way as to effect adequate sealing and in such way as to avoid undesirable and hazardous overhangs or projections. Such closing device or slack take up member is designed to be rocked or rotated on one or the other of its ends in order to shorten the straps whereby it is coupled to the chime ends, the straps having a certain order or degree of resiliency to admit of the operation stated and to insure conformability.

The slack take up member is a rigid link generally designated 11 and comprising side bars or cheeks 12 joined by rounded end bars 13 jour-

nalled in strap extensions 14 and 15 of the U-ring or chime. According to my present improvements strap extension 14 is a continuation of the unchannelled portion of the ring doubled upon itself to provide an end loop or journal 16 and thence continued in lapping relation with itself and with the external wall of the ring an effective distance to provide for the mounting of a screw stud 17 constituting one member of a mated interlock for securing the parts in the closed position. The other strap extension 15 cooperates with a metallically secured externally applied leaf 18 having an intermediate looped portion 19 constituting another journal bearing for the slack take up member. The so stiffened or plied ends 18 of this strap extension are formed with an elongated slot or eye 20 which in the contracted or closed position of the chime is adapted to register with and to be engaged by the screw stud 17 and secured in such relation by a complementary nut 21.

As in the device of my prior application aforesaid one of the side cheeks of the slack take up member may be provided with a laterally offset eye or loop 22 and it will be manifest that by inserting a screw-driver or other implement therein member 11 may be rocked on one of its end axes, the effect of which is to lap the respective strap extensions, thereby contracting the chime and putting the respective parts of the interlock in mated relation.

Having described my invention, I claim:—

1. The combination of a container having an opening whose defining wall is formed with a gasket seat, a gasket, a cover having a flange 35 which bears upon the gasket, and means for sealing and securing the parts in the relation stated, said means comprising a horizontal U-chime having spaced apart ends with strap extensions whereof each carries a mate of a mated interlock for securing the chime in the contracted state, a slack take up member mounted for angular movement with relation to the straps to contract the chime and to put the mated locking provisions in interengaging relation, said mated locking provisions comprising male and female members, and a separable member for securing them in locking position.

2. The device set forth in claim 1, in which one of the straps is provided with a stud to engage a complementary eye in the other strap when the chime is in its contracted state.

3. The device set forth in claim 1, in which a substantially flat part of the chime is doubled upon itself to provide a journal bearing for the 55

slack take up member and to provide an external stiffening member to insure adequate anchorage of one of the mated locking members.

4. The device set forth in claim 1, in which a strap extension of the chime cooperates with an externally applied stiffening member to provide a journal bearing for the slack take up member and one member of a mated interlock.

5. The device set forth in claim 1, in which one of the straps is provided with a screw stud and the other strap is provided with a slot to accommodate the stud when the chime is contracted, and a nut in abutting relation with the slotted strap and engaging the stud to hold the parts in locked position. 5

EDGAR E. SHANOR.
